UNITED STATES PATENT OFFICE.

RICHARD MAX GADOW, OF BILLINGS, MONTANA.

RAILROAD-CROSSING EVENER.

1,323,975.

Specification of Letters Patent.

Patented Dec. 2, 1919.

Application filed July 10, 1919. Serial No. 309,872.

To all whom it may concern:

Be it known that I, RICHARD M. GADOW, a citizen of the United States, residing at Billings, in the county of Yellowstone and

5 State of Montana, have invented certain new and useful Improvements in Railroad-Crossing Eveners, of which the following is a specification.

This invention relates to crossings of rail-10 ways with roads or streets.

The object of the invention is to provide a simple, cheap and efficient evener to permit the smooth passage of vehicles across a railroad track and yet not interfere with 15 the safe passage of a train over the rails.

Another object is to so construct such an evener that it will automatically lower on the passage of a train thereover to permit the engagement of the rails by the flanges 20 of the car wheels, and return to raised operative position after the train has passed.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made 30 within the scope of what is claimed without departing from the spirit of the invention.

In the accompanying drawings:—

Figure 1 represents a side elevation with 35 parts broken out and in section of the evener constituting this invention shown applied,

Fig. 2 is a top plan view thereof,

Fig. 3 is a transverse vertical section,

Fig. 4 is an enlarged detail plan view of 40 a portion of the evener,

Fig. 5 is a vertical transverse section taken on the line 5—5 of Fig. 4,

Fig. 6 is a detail vertical section taken on the line 6—6 of Fig. 5, and

45 Fig. 7 is a transverse section taken on the line 7—7 of Fig. 1.

In the embodiment illustrated, the evener constituting this invention comprises an auxiliary rail 1 mounted at one side of a 50 railroad rail R between it and the platform

P, the latter being spaced from the rail R a sufficient distance to permit the flanges of the car wheels to pass between said platform and the railroad rail.

The platform P which is usually placed 55 between the track rails R and on the outside thereof, is positioned flush with the treads of said rails and at one side is spaced from said rails a sufficient distance to permit the passage of the car wheel 60 flanges. The space so formed is objectionable for many reasons, one being that it makes a ridge which jars vehicles passing thereover, and another that it becomes filled with dirt, and interferes with the car wheel 65 flanges passing over the rails R.

To overcome these objections, the evener constituting this invention is designed and operates as a vertically movable filler between platform P and rail R as is shown 70 clearly in Fig. 3. This evener comprises an auxiliary rail 1 supported by coiled springs 2 disposed between supporting blocks or posts 7 and the rail 1. This rail has a recess 1^a in its lower face and telescopically 75 engages a solid rail 14 fixed to posts 7, the lower edges 1^b of rail 1 being sharpened to cut away ice and mud from rail 14 as it moves vertically thereon. Rail 14 has vertical openings 15 to form housings for the 80 springs 2. The coiled springs 2 encircle bolts 3 which pass through the rails 1 and 14 and through the blocks 7, being secured by means of nuts 8 which slide in apertures 9 in the posts or blocks 7. These bolts 3 85 have heads 3^a which are guided by the walls of the socket 4 and are retained therein by fastening means presently to be described.

The apertures 5 in the rail 1 through which the bolts 3 pass have outwardly 90 flared side walls 6 which permit the bolts to move laterally when the rail 1 is depressed at either end and elevated at its opposite end, such as occurs when a train passes over the crossing. These bolts have threaded engagement with the sliding blocks or nuts 8 and said blocks limit the upward movement of the rail 1 by abutting against the top wall of the opening 9 in each block 95 7 as is shown clearly in Figs. 1 and 3. 100

The means shown for retaining the bolts in the sockets 4 against upward movement, comprise latch members in the form of bars 11 which are pivotally mounted at one end in upstanding apertured lugs 12, one of which is arranged at the bottom of each socket 4 at one side of the aperture 5 therein, being spaced from said aperture a sufficient distance to permit the head of the bolt to rest on the bottom of the socket over the aperture. The bar 11 spans the bolt head and is engaged at its free end with a hook-shaped catch 13 rising from the socket bottom at a point diametrically opposite to the apertured lug 12. These latch bars 11 will thus operate to hold the bolts 3 securely engaged with the rail 1 and prevent them from rising when a train passes over and depresses rail 1. To prevent these sockets 4 from filling up with dirt, water or the like, they should be closed by suitable plugs, not shown.

To prevent the auxiliary rail 1 from sliding longitudinally, end thrusts 10 are mounted at each end thereof and are preferably constructed as shown in Fig. 1, being secured to one of the railway ties, and having an upstanding abutment 14 positioned in alinement with the rail 1 to take the end thrust thereof when the rail is in elevated position.

From the above description it will be obvious that the springs 2 will operate to hold the rail 1 raised with its upper face flush with the tread of rail R and with the upper faces of the platforms P disposed at opposite sides of said rail. When a train passes over the crossing, the flanges of the wheels will force the auxiliary rail 1 downward against the tension of springs 2, which causes the blocks 8 to move downward in the slots 9 and after the train passes over the crossing, the springs will restore the evener 1 to normal position shown in Figs. 1 and 3.

It will be obvious that the vertical movement of the auxiliary rail 1 will operate to keep the space between rail R and platform P free of dirt, snow, ice and the like, and thus obviate the necessity of employing help to clean out the grooves which are usually found in the platforms of railroad crossings at this point.

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the best embodiment thereof, I desire to have it understood that

the device shown is merely illustrative and that such changes may be made as are within the scope of the claimed invention.

Having thus fully described my invention, what I claim as new and desire to secure by Letters Patent, is:—

1. A device of the class described comprising a vertically movable auxiliary rail, supporting blocks positioned below said rail and spaced vertically therefrom, bolts depending from said rail, coöperating means carried by said bolts and blocks for guiding the rail in its vertical movement, and coiled springs encircling said bolts between the lower face of said rail and said blocks.

2. The combination with a track rail; of a platform with its upper face flush with the tread of said rail and spaced at one side from said rail, a vertically movable auxiliary rail disposed in and filling the space between said platform and track rail, supporting blocks positioned below said auxiliary rail and spaced vertically therefrom, bolts depending from said auxiliary rail, coöperating means carried by said bolts and blocks for guiding the auxiliary rail in its vertical movement, and coiled springs encircling said bolts between the lower face of said auxiliary rail and said blocks.

3. The combination with track rails; of a platform arranged between said rails and spaced at its side edges from the rails, a vertically movable auxiliary rail positioned in each space so formed, said auxiliary rail having apertures extending vertically therethrough at longitudinally spaced points, the upper portions of said apertures being enlarged to form sockets, and their lower portions flared outwardly, bolts passing through said apertures with their heads seated at the bottom of said sockets, means spanning said bolt heads to hold them in fixed relation to the rail, supporting blocks arranged below and spaced from said auxiliary rail and having cut-out portions therein, said bolts extending into said cut-out portions, guide blocks carried by said bolts and movable in said cut-out portions, and coiled springs on said bolts between the tops of said blocks and the lower face of said rail.

4. The combination with track rails; of a platform arranged between said rails and spaced at its side edges from the rails, a vertically movable auxiliary rail positioned in each space so formed, said auxiliary rail having its under face recessed, a fixed rail with which said auxiliary rail telescopes, transversely, and springs supporting said auxiliary rail.

5. The combination with a track rail; of a platform with its upper face flush with

the tread of said rail and spaced at one side from said rail, a vertically movable auxiliary rail disposed in and filling the space between said platform and track rail, supported by blocks positioned below said auxiliary rail and spaced vertically therefrom, a rail fixed to the upper faces of said blocks, said auxiliary rail being recessed on its lower face to receive said fixed rail, said rails having registering apertures extend-

ing vertically therethrough, bolts extending through said apertures, and coiled springs on said bolts to support said movable rail.

In testimony whereof I affix my signature in presence of two witnesses.

RICHARD MAX GADOW.
